United States Patent Office.

ELISE DE BUSSON, OF YONKERS, NEW YORK.

Design No. 4,667, dated February 21, 1871.

DESIGN FOR A SPOON.

The Schedule referred to in these Letters Patent and making part of the same.

To all whom it may concern:

Be it known that I, ELISE DE BUSSON, of Yonkers, in the county of Westchester and State of New York, have invented a new and original Design for Spoons; and I do hereby declare that the following is a full, clear, and exact description thereof, which will enable others skilled in the art to make and use the same, reference being had to the accompanying drawing forming part of this specification.

The invention relates to spoons, and consists in a design for a new relative configuration of parts.

The bowl is, by itself, that of ordinary spoons, and the same may be said of the handle; but, as seen in

the drawing, the spoon presents the open bowl at right angles to the front of the handle, and, consequently, bent near the intermediate point of connection on one of the edges.

Having thus described my invention,

What I desire to protect by Letters Patent, is—

The handle and bowl of an ordinary spoon placed in the relation to one another shown in the drawing, and above described, to form a new design for a spoon.

ELISE DE BUSSON.
